L. GOTTFRIED

INVISIBLE GARMENT POCKET

Filed March 13, 1924

UNITED STATES PATENT OFFICE.

LEOPOLD GOTTFRIED, OF PHILADELPHIA, PENNSYLVANIA.

INVISIBLE GARMENT POCKET.

Application filed March 13, 1924. Serial No. 698,825.

To all whom it may concern:

Be it known that I, LEOPOLD GOTTFRIED, a citizen of the United States, residing at the city of Philadelphia, in the county of 5 Philadelphia and State of Pennsylvania, have invented certain new and useful Improvements in Invisible Garment Pockets, of which the following is a specification.

My invention has relation to the production in a garment as a coat or similar article of apparel, an invisibly non-sagging or bulging pocket, bellows-like in formation; and in such connection my invention relates to the invisible character of the pocket viewed 10 from the outward appearance of the same; the flap only covering the opening into the pocket being visible; further my invention comprehends in the defined type of pocket of one that will not sag or bulge 15 from expanding or cannot become distorted from any normal or abnormal use of the same; but will reassume a bellows-like closed condition, when the expanding or distorting influences are removed; and further 20 such a pocket as that applied to the garment its contour or outline is invisible from the face of the garment, it being fashioned from the inner side and connected with the garment so that the two sides and bottom 25 of the pocket are free of both the garment material and insert, a flap-strip, with which a silk or satin material creased strip is connected and with the body material of the garment, and so combined and arranged 30 therewith as to form the bellows-like effect 35 in order that in expanding or distorting the pocket, it will thereafter be relieved of bulging as well as subsequent sagging from use, whether such action be of a normal or 40 abnormal character.

My invention stated in general terms, consists of an invisible garment pocket constructed and arranged in bellows-like form, to prevent bulging from use, as well as subsequent sagging and so formed as that after expanding or distorting influences are relieved, the pocket will assume its normal condition, that is, the garment from its outward appearance will present a flat surface flap, 45 which forms the covering to the opening of the pocket concealed to view.

In the further disclosure of my invention reference is made to the following specifications, and to the accompanying drawings forming part of this specification, in 50 which—

Figure 1 is a front elevational view of an invisible type of garment pocket, embodying the face appearance of the same.

Fig. 2 is a rear elevation view of the formation of the bellows-like pocket, in detail.

Fig. 3 is a transverse sectional view on the line 3—3 of Fig. 2; and

Fig. 4 is a vertical sectional view on the line 4—4 of Fig. 2.

Referring to the drawings *a*, represents the garment body material from which the entire garment, such as a coat or similar article is made. *b*, is the opening provided in 70 and forming part of the pocket *c*, positioned by stitching *c'*, crosswise of the garment material, about the opening *b*. A flap *d*, is provided, covering the said opening and lying flat against the body material of the 75 garment *a*, as clearly illustrated in Fig. 1, and is the only visible element of the existence of a pocket in the garment, viewed outwardly thereof.

The rear of the garment is provided with 80 a depending flap *e*, having a free edge disposed adjacent and substantially parallel with the pocket slot in the garment, and a flap *g*, disposed at right angles to the flap *e*, with its free edge depending downwardly 85 from a point adjacent one end of the pocket slot. The pocket *c* is protected and concealed on its inner side by an inner protecting strip *f*, of a larger area than said pocket, and adapted to overlie the same. 90 The upper edge of the strip *f* is secured by stitching *e'*, to the free edge of the flap *e*, and one side thereof is secured at a point adjacent its edge, to the free edge of the flap *g*, by stitching *g'*, said stitching also 95 securing a piping to the edge of this flap. The other side edge and bottom of the strip *f* is secured to the garment *a*, by a pleated binder of silk or of any desired material. This binder has a piped edging *f'*, secured 100 to the side and bottom of the strip *f*, and folding sections *f''* and *f'''*, which are adapted to allow the pocket *a* limited expandable movement, but tend to return it to normal position by the folded pleated relation of 105 these sections. The other edge of the binder *f'* is secured to the garment.

By this arrangement the protecting strip *f*, is so fashioned to position on the rear side of the garment material *a*, as to assume 110 a condition against distorting it, yet enabling the functioning of the flap in a bel-

lows-like manner, when anything is inserted in the pocket *c*, free from the flap, but with the ability of the said strip *f*, to compensate for any expanding or even distortion of 5 the pocket, without when relieved of such, it being so maintained, but so arranged as to assume its normally flat invisible condition, to all outward appearances of the garment.

10 The structural arrangement of the hereinbefore defined invisible surface pocket, is not only inexpensive to provide, involving in formation but few elements, but it is also readily pressed without a bulging effect or wrinkling of the cloth; and moreover, far more so than is the case of pockets such as are now generally to be found in ordinary apparel garments.

I claim—

20 1. The combination with a garment having a slot and a flap covering the same, inner flaps on the garment having loose free edges adjacent to said slot and at transverse angular relationship thereto, of a concealed 25 pocket having the mouth portion connected with the edge of the slot, an inner pocket

protecting strip larger in extent than the pocket and a binder connecting one side edge and bottom of the strip to the garment and the other side of the strip and top being 30 secured to the free edges of the inner flaps.

2. The combination with a garment having a slot and an outer flap covering the same, inner flaps on said garment having loose free edges adjacent the top of the slot 35 and at right angles thereto, of a concealed pocket having its mouth portion secured to the edge of said slot, an inner pocket protecting strip of a slightly larger area than said pocket, a pleated binder connecting one side edge and the bottom of said strip to the garment, and the other side of said strip and its top being secured to the free edges of the inner flaps.

In witness whereof, I have hereunto set 45 my signature in the presence of the two subscribing witnesses hereto.

LEOPOLD GOTTFRIED.
